Edward G. Markley Inventor, by
Ch. Sidney Whitman Attorney,

United States Patent Office.

EDWARD G. MARKLEY, OF SUNBURY, PENNSYLVANIA.

Letters Patent No. 101,751, dated April 12, 1870.

IMPROVEMENT IN RAILWAYS.

The Schedule referred to in these Letters Patent and making part of the same.

To all whom it may concern:

Be it known that I, EDWARD G. MARKLEY, of Sunbury, in the county of Northumberland and State of Pennsylvania, have invented a new and useful Improvement in Railroad Sills; and do hereby declare that the following description, taken in connection with the accompanying plate of drawings hereinafter referred to, forms a full and exact description of the same, wherein I have set forth the nature and principles of my said improvement, by which my said invention may be distinguished from others of a similar class, together with such parts as I claim and desire to secure by Letters Patent.

My invention relates to that class of railroad superstructure, the office of which is to support, connect, and hold in position the rails, and the nature thereof consists in certain modifications in the details and improvements in the construction of the same, by means of which the rails are so coupled or jointed as to maintain a perfect level; the use of wooden sills or cross-ties is done away with; the necessity of preparing the bed-road obviated; economy of construction facilitated; durability insured.

The design or object of my invention is to supersede the present mode of constructing railroad superstructure, to dispense with wooden sills, chairs, spikes, &c., and to substitute an arrangement of devices which will combine economy and safety of travel.

In the accompanying plate of drawings which illustrates my invention, and forms a part of the specification thereof, in which corresponding parts are illustrated by similar letters—

Figure 1 is a side elevation;

Figure 2 represents a plan;

Figure 3, a transverse vertical section; and

Figure 4 is a plan view.

The construction, operation, and relative arrangement of the component parts of my invention are as follows, to wit:

A represents an upright block, constructed of cast-iron, and having the form of a truncated cone.

Upon the top of the said cone, and constructed of one and the same piece therewith, is flanch B, which forms the chair in and upon which the rails rest.

Upon the top of the said flanch is cast the elongated tapering slot D, provided with shoulders d to fit the rail and the wedge-shaped key E.

Upon the lower side of the said key is cast the shoulder e, and upon the upper side thereof the shoulder e', which fit respectively in the receptacles in the flanch and rails, as shown.

The conical block A is hollow, and may be pro-

vided with shoulders a, upon which can be placed a pad of wood or rubber to ease off the downward pressure of the rails.

Upon one side of the said block is cast or otherwise secured, the eye-bolt F, in which is fastened the tie H, which connects the said block with its fellow on the opposite side of the track.

To secure the rails I upon and within the flanch or seat B the said rails are so placed that the ends thereof rest upon the center of the seat, and one side of the broad bottoms thereof is introduced within the receptacle cast for its reception, as aforesaid. The key E is then introduced and fitted, as hereinbefore described, in such a manner as to hold the rail firmly in position.

After being so introduced, the key is held in position by means of a pin, e², passing through a perforation cut therein. By this means the rails are firmly and evenly united within the embrace of the chair and key.

The connecting-tie H extends across the road from one block to the other, and is located at such a distance from the top thereof as to be sunk below the grade of the road and covered over with earth. By this arrangement the sills opposite to each other on either side of the road will be bound together in such a manner as to resist any lateral pressure produced by heavy trains passing over the rails, and the necessity of preparing a bed for cross-ties obviated.

The bottom of the block A may be provided with a flanch sufficiently broad to maintain the uprightness thereof when inserted in the ground. The bottom or base of the receptacle for the reception of the block may be filled in with a few inches of pounded stone, with a top dressing of a little earth well rammed down and made perfectly level. But when the earth is of solid texture this operation may be omitted. The block may be constructed of such a size as to extend downward below the reach of the effects of frost, thereby obviating difficulties occasioned thereby.

Having thus described my invention,

I will indicate what I claim, and desire to secure by Letters Patent, in the following clause:

The hollow conical block A, provided with the elongated tapering slot D for the reception of the key E, and constructed with shoulder a for the reception of an elastic pad, when combined with the rails I, as and for the purpose described.

EDWARD G. MARKLEY.
